UNITED STATES PATENT OFFICE.

CHARLES EVAN FOWLER, OF DETROIT, MICHIGAN, ASSIGNOR TO FOWLER ENGINEERING CORPORATION, OF NEW YORK, N. Y., A CORPORATION OF NEVADA.

THEATER STRUCTURE.

Application filed April 11, 1923. Serial No. 631,426.

To all whom it may concern:

Be it known that I, CHARLES EVAN FOWLER, a citizen of the United States of America, at present residing in Detroit, in the county of Wayne and State of Michigan, have invented a new and Improved Theater Structure, of which the following is a description.

My invention relates to theaters and more particularly to a theater for motion pictures. The usual type of theater construction for motion pictures is objectionable because it makes it necessary that too many people sit close to the screen for which reason and for the further reason that the people coming and going constantly interrupt the view of those in front of them, the result is produced of seriously impaired eyesight in the patrons of such theaters, the impairment being in the direction of a complete loss of eyesight.

The general object of my invention is to provide a theater structure in which the cause of producing impaired eyesight in the patrons will be eliminated, or at all events, minimized.

A further object of the invention is to provide a theater structure reflecting practical considerations with respect to the convenient seating and emptying of the house or sections thereof.

The nature of the invention and its characteristic features and advantages will clearly appear as the description proceeds.

Reference is to be had to the accompanying drawings forming a part of this specification, it being understood that the drawings are merely illustrative of one example of the invention.

Figure 1 is a plan view of a theater structure embodying my invention, parts being broken away;

Figure 2 is a longitudinal vertical section in a plane indicated by the line 2-2 in Figure 1.

In carrying out my invention in accordance with the illustrated example I provide within the theater a series of oblique truss beams 10 extending from the orchestra floor upwardly and forwardly toward the front wall A of the structure. Any suitable support may be provided for the upper end of the beam 10 either in the way of walls, columns, or roof trusses. Intermediate the ends of the truss beams 10 each has support on columns 110 in the illustrated example.

Beneath the trusses between the same and the front of the theater are landings 11. Connecting several of the lower landings with one another any suitable means may be provided in the way of ramps, elevators, or stairways, there being indicated in the present example stairs 12. Those of the landings 11 nearest the top are advantageously connected by a line of stairs 13 adjacent the front wall to economize space as the space between the front wall and the truss beams 10 decreases.

In the illustrated plan the numeral 14 indicates the orchestra which may have orchestra chairs. 15 indicates the orchestra enclosure; 16, the stage; 18, the screen which is at the extreme back of the theater, therefore at the rear of the stage; and 17 indicates the proscenium arch which in carrying out my invention is made much higher than the usual proscenium arch.

In accordance with my invention I provide a series of balconies 19 one above another and set back in cascade or stepped form so that the front portion of one balcony will be visible from the balconies above. By reason of the increased height of the proscenium arch 17 the complete visibility of the screen 18 is provided for, even from the uppermost balcony which may thus be disposed at a higher elevation than is usual with balconies.

Upper balconies 19 are disposed at a slight angle the angle decreasing to the lowermost one or two which may be disposed horizontally or approximately so.

Each balcony is disposed elevated above that landing 11 from which said balcony is reached. The balconies are sustained by props 20 rising from the rear portion of one balcony at the juncture of the balcony with the trusses 10, said props being secured to the next balcony above between the front and rear of the latter balcony.

To reach a balcony from a landing below a series of stairs 21 is provided, there being a plurality of such stairs from each landing leading to each balcony at aisles 22 of which there are a plurality in each balcony.

The aisles 22 of a balcony in practice divide the balcony into sections and each section may have seats 23 accommodating four persons, that is, between two adjacent aisles so that two persons may be seated in said seats 23 from each of two adjacent aisles,

thereby interfering to the minimum extent or not at all with the view of those seated behind in the same section.

The described arrangement permits of seating the patrons in units corresponding with the respective sections in a balcony so that the different sections of the balcony may be sold one after the other whereby the patrons in each section of a given balcony would leave the theater at the same time and thereby making it possible by rotation of ticket sales to reduce or entirely prevent any interference at all with others viewing the picture, such interference characterizing the present theater arrangement and being highly objectionable. Other seating plans may be adopted.

The structure described is very advantageous in providing a greatly increased seating capacity over the usual motion picture theater of a given size. The arrangement also is advantageous in that enough people will be in view on each balcony to measurably attain the desirable psychological effect of having many people in view at one time. The greatest merit, however, of the arrangement described is that a seating capacity for a large audience is provided without any of the audience being seated so close to the screen as to have their eyesight injuriously affected and this purpose is attained by a structure characterized by strength and simplicity.

It will be observed that the described construction provides trusses in a plane transecting the orchestra floor and oblique to the front wall; that the trusses are common to all the balconies, that the aisles of the orchestra and the aisles of the respective balconies are disposed between said trusses. The individual stairs leading from the landings to the balconies above the respective landings are independent of the stairs or equivalent means establishing communication between the respective landings.

It is further to be noted as important that a triangular structure results from the use of the oblique beams which it will be observed form with the foundation and the front wall. A rigid triangle and a second minor triangular formation is produced by the oblique beams, the supporting columns, and the under structure on which said columns have base support.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

1. In a theater structure, a series of bal-

conies one above another and successively set back from the lowermost one upwardly, a series of supporting beams beneath said balconies, said beams rising obliquely at an angle to the front of the structure, a series of landings one above another beneath said beams between the same and the front of the structure, means establishing communication between the respective landings, and stairs at the landings, said stairs rising from the landings to the respective balconies above.

2. In a theater structure, a series of balconies one above another and successively set back from the lowermost one upwardly, a series of supporting beams beneath said balconies, said means being in the form of trusses and rising obliquely at an angle to the front of the structure, the beams terminating at the top adjacent the juncture of the front wall and roof of the structure, a series of landings one above another beneath said beams between the same and the front of the structure, means establishing communication between the respective landings, and stairs at the landings, said stairs rising from the landings to the respective balconies above at the respective aisles of said balconies.

3. In a theater structure, a series of balconies one above another and set back successively from the lowermost one upwardly one overlying the other, and a series of supporting beams, beneath and common to the several balconies, said beams rising obliquely from below the balconies toward the front wall of the structure and disposed in the rear of the balconies, said balconies being thus disposed projecting forwardly from the plane of the beams to lie forward of the beams.

4. In a theater structure, a series of balconies one above another and set back successively from the lowermost one upwardly one overlying the other, and a series of supporting beams beneath and common to the several balconies, said beams rising obliquely from below the balconies toward the front wall of the structure; together with means between the beams affording access to the balconies.

5. In a theater structure, a series of balconies one above another and set back successively from the lowermost one upwardly one overlying the other, and a series of supporting beams disposed obliquely beneath and common to the several balconies, the upper ends of the beams having support adjacent to the top of the front wall, a proscenium arch, and a screen disposed at the back of the theater in the rear of said arch and visible from all of said balconies.

6. In a theater structure, a series of balconies one above another and successively set back from the lowermost one upwardly, a series of supporting beams beneath said balconies, said beams rising obliquely at an

angle to the front of the structure, a series of landings one above another beneath said beams between the same and the front of the structure, means establishing communication between the respective landings, and stairs at the landings, said stairs additional to and independent of said means establishing communication between the respective landings.

10. 7. In a theater structure, a series of balconies one above another and successively set back from the lowermost one upwardly, a series of supporting beams beneath said balconies, said beams rising obliquely at an angle to the front of the structure, a series of landings one above another beneath said beams between the same and the front of the structure, means establishing communication between the respective landings, and stairs at the landings, said stairs additional to and independent of said means establishing communication between the respective landings, said stairs furthermore rising from the landings to the respective balconies immediately above the respective landings.

8. In a theater structure, a series of balconies one above another and set back successively from the lowermost one upwardly, and a series of beams common to the several balconies, said beams extending obliquely upward from the plane of and transecting the orchestra floor toward the front wall of the structure, the orchestra floor and the several balconies having aisles between said beams; together with means between the beams for reaching the several balconies.

9. In a theater structure, a series of balconies one above another and set back successively from the lowermost one upwardly, and a series of beams common to the several balconies and disposed in a plane oblique to the planes of the balconies and oblique to a vertical plane; together with means constituting the support for said beams and completing with said beams a rigid funda-

mental triangular formation carrying to the ground and disposed at the back of the beams.

10. In a theater structure, a series of balconies and a series of beams common to the several balconies and affording support therefor; together with means forming with said oblique beams a rigid fundamental triangular formation carrying to the ground and disposed at the back of the beams.

11. In a theater structure, a series of balconies one above another and set back successively from the lowermost one upwardly to overlie one another, a series of beams oblique to a vertical plane and transecting the planes of the several balconies and means coordinating the balconies with the beams and supporting the balconies in rigid relation to one another and to the beams, said means affording support for said balconies from said oblique beams.

12. In a theater structure, a series of balconies one above another and overlying one another, a series of beams oblique to a vertical plane and transecting the planes of the several balconies, and means coordinating the balconies with the beams and affording support for said balconies from said oblique beams in rigid relation to one another and to said beams.

13. In a theater structure, a series of balconies one above another to overlie one another, a series of beams oblique to a vertical plane and transecting the planes of the several balconies, and means coordinating the balconies with the beams and affording support for said balconies from said oblique beams in rigid relation to one another and to the beams; said balconies having aisles running in planes alternating with the vertical planes of the oblique beams, and transversely disposed seats extending from one aisle to an adjacent aisle and across the vertical planes of the beams.

CHARLES EVAN FOWLER.
